CLAIM

The ornamental design for a loudspeaker enclosure, as
shown.

DESCRIPTION

FIG. 1 is a front, top and left side perspective view of a
loudspeaker enclosure showing my new design;

FIG. 2 is a front elevational view thereof;

FIG. 3 is a left side elevational view, the right side being
a mirror image thereof;

FIG. 4 is a top plan view thereof, the bottom being a
mirror image thereof;

FIG. 5 is a rear elevational view thereof.
